UNITED STATES PATENT OFFICE.

OLIVER P. LUETSCHER, OF PITTSBURGH, PENNSYLVANIA.

STOKER.

Application filed March 13, 1922. Serial No 543,221.

My invention relates to stokers and is directed particularly to stokers for industrial furnaces although not limited to that particular field.

5 In such machines the fuel is ignited and the fire bed formed at the upper edge of a retort, the burning fuel overflowing on both sides of the retort and spreading itself out on side grates. In some stokers as heretofore constructed these side grates take the form of dead plates as there is no wind box surrounding the retort and all of the air to the tuyères comes from a space below the fuel bed which might be designated as the 10 ash pit, but no ash can enter it except a little of the siftings that may come through the tuyères.

Observation of the action of such stokers discloses the fact that when the fire is first 20 lighted or freshly cleaned the coal begins to burn on top of the retort immediately above the tuyères and with the usual rate of feeding a high combustion rate is necessary to consume the amount of coal fed. Consequently a bed of clinker is formed which 25 arches over the retort. This is forced upward by the incoming fuel and spreads the blast over a greater area by forcing it to take a path underneath the cap of clinker. This 30 action continues with more or less severe clinkering until sufficient clinker has been formed to spread the blast out over an area large enough to bring the rate of combustion down to a point at which the fuel bed temperature is below the fusing point of the 35 ash.

From the foregoing it will be quite obvious 40 that stokers of this type can not operate without severe clinkering especially if capacities are maintained which are comparable with the rated capacities of the machines based on their actual continuous fuel burning capacity.

The inherent difficulty of such machines is 45 that there is no efficient means for retarding the combustion at the tuyères to prevent the extremely high temperatures and at the same time supply sufficient air to complete the combustion.

50 My invention overcomes these and other objections by providing means for introducing a primary blast of moist air through the tuyères and means for controlling the composition of this blast so that the temperature in the region of the retort may be accurately 55 controlled to avoid clinker and build up a

coke bed. Means are also provided for supplying a secondary blast through the side grates for the purpose of maintaining combustion in that area.

60

By the use of my invention a stoker is provided which may be readily removed from the furnace without disturbing the permanent furnace setting. My stoker is so constructed that the tuyères may be readily removed as units without disturbing any substantial part of the stoker.

65

Further advantageous mechanical and operative features will be apparent upon reading the following description in connection 70 with the drawings showing one embodiment of my invention and in which:

Figure 1 is a front elevation of a furnace with my invention applied thereto;

Figure 2 is a vertical section on line II—II 75 of Figure 1;

Figure 3 is a section on line III—III of Figure 2;

Figure 4 is a section on line IV—IV of Figure 2;

80

Figure 5 is a section of the rear end of the tuyère taken on a plane through the line V—V of Figure 6;

Figure 6 is a perspective view of a portion 85 of the tuyère;

Figure 7 is a front view, with certain parts removed, of a modification of my invention, and

Figure 8 is a side elevation of a part of the 90 stoker shown in Figure 7, with certain parts broken away.

Referring to the drawings and particularly to Figure 1, a furnace 1 of any well known construction is shown having buck 95 stays 2 and doors 3 and 4, with my stoker applied thereto.

The stoker is provided with a removable hopper 5 through which the coal is fed into the pusher 6 as best shown in Figure 2. The pusher 6 may be of any desired construction 100 and is reciprocated by a piston 7 in a cylinder 8 by means of a piston rod 9 which is attached to the pusher in any suitable manner. The pusher is provided with guides 10 as shown in Figure 3 which run in guideways 105 in the main frame 11 which is stationary normally and supported from the foundation. Steam pipes 12 and 13 are provided for supplying steam for actuating the piston 7. The pipes 12 and 13 communicate with any desired valve mechanism whereby steam is controlled to actuate the piston. The stoker is 110

provided with a retort 14 which is also supported at its front end by the main frame 11 of the desired shape and strength. The retort is shown in detail in Figure 4 and is provided with a chamber 16 through which water or other cooling medium may be circulated for a purpose which will appear later. The retort is of the general shape shown in Figure 4 and slopes upwardly from the front 10 of the furnace as shown in Figure 2. The retort is supported at one end by the frame 11 and at the other end by a casting 17 fastened in the wall 18 of the furnace and provided with a flange 19 upon which the inner end of 15 the retort rests.

The retort is provided at its sides with horizontal portions 20 and 21. An upstanding flange 22 is provided on each of the portions 20 and 21. Tuyères 23 and 24 are 20 mounted on the portions 20 and 21, respectively, of the retort as shown in Figure 4.

The tuyères comprise holders 25 which may be made of cast steel. The holders are hollow box-shaped members provided with 25 grooves 26 and 27 and flanges 28 and 29 as shown in Figures 4 and 6. Tuyère blocks or segments 30 are provided with tongues 31 and 32 which fit into the grooves 26 and 27, respectively. These blocks are also provided 30 with projections 33 and 34 which bear against the edges of the holders 25 as shown in Figure 6. Each of the blocks 30 is provided with recesses 35 in one side thereof so that when the blocks are assembled as shown in Figure 6 35 openings are produced which communicate with the interior of the holders 25. The end block 36 is provided with a portion 37 which extends across an opening 38 in the end 39 of the holder 25. The part 37 is provided 40 with an opening which registers with the opening 38 and a bolt 40 is passed through these registering openings and acts to hold the section 36 in place on the holder. The other blocks 30 extend the length of the 45 tuyère, the last one being placed against the block 36 as shown in Figure 5 so that all of the blocks are held against rearward longitudinal movement on the holder for a purpose which will appear later.

50 Side grates 41 are placed in the combustion chamber of the furnace and are supported therein independently of the retort or tuyères.

Pipes 42 and 43 connect with the tuyères 55 as shown in Figures 1 and 2. These pipes communicate with an Argand blower 44 as best shown in Figure 2. The pipes 42 and 43 are provided with sliding dampers 45 and 46 respectively, for the purpose of regulating 60 the blast to the tuyères. These dampers are arranged to slide in recesses formed in the flanges at the junctions of the sections in the pipes, while the stems connected to the valves extend to the exterior of the pipes, as shown 65 in Figs. 1 and 2. The construction of the

Argand blower is well understood and it has been deemed unnecessary to illustrate the same in detail in the drawings. Obviously any other well known means may be employed in place of the Argand blower and my invention is not limited to any particular form of blower. As is well understood the Argand blower is so constructed that the proportions of air and steam passing therethrough may be changed by an adjustable air 70 shutter with which said blower is equipped. 75

The wall 18 is provided with an opening 47 into which a pipe 48 is fitted and through which a blast of air is introduced to the ash pit 49.

80 The main frame 11 is supported by filler blocks 50. Filler blocks 51 are also provided under a pedestal 52 for the purpose of rendering the stoker easily removable from the furnace as will appear later. As will be noted by reference to Figure 2 the frame 11 of the stoker when in position snugly fits into the door frame 53 in the furnace wall 54. A space is provided between these members in which a packing material 55 is placed to prevent the 85 escape of air.

90 The modification shown in Figures 7 and 8 will now be described. The parts corresponding to similar parts in the modification shown in the other figures have been given the same numerals with the letter *a* affixed thereto.

95 The main frame 11^a carries the stoker construction and fits into a door frame 53^a in the wall 54^a of a furnace. Instead of the Argand blower shown in Figure 2, I have substituted 100 a wind box 60. This box is provided with an operating rod 61 extending across the same and journaled in the sides thereof. The ends 62 of the rod are squared for the purpose of rotating the rod by means of a handle which may be applied thereto. A bifurcated lever 63 is attached to the rod 61 and through a link 64 actuates a damper 65 which slides on the bottom of the wind box. The frame 11^a is provided with an opening 66 which opens 105 into the ash pit so that when the damper 65 is open the blast which is forced into the wind box will pass through the opening 66 into the ash pit. Pipes 42^a and 43^a connect with the sides of the wind box and lead upwardly to 110 the tuyères as in the construction shown in Figures 1 and 2. Water spray nozzles 67 are mounted in the elbows of the pipes 42^a and 43^a for the purpose of moistening the air as it goes into the tuyères. The nozzles 67 may 115 be of any well known construction and have therefore not been shown in detail. These nozzles are mounted in sleeves 68 which are screwed into the pipes 42^a and 43^a. Water pipes 69 are screwed into the sleeves 68 and are connected with any suitable source of 120 water supply. The air which enters the wind box 60 may be preheated to any desired degree by any suitable means and is forced into the wind box by any desired form of blower. 125 130

The operation of my device is as follows: The stoker is moved into the position shown in Figure 2 and the hopper is filled with coal and the pusher 6 reciprocated by the piston 7. 5 This fills the retort with coal which is ignited. The primary blast through the Argand blower 44 is introduced and the blower is suitably adjusted to meet the conditions in hand and a mixture of steam and air is supplied to the tuyères through the pipes 42 and 43, the same being individually regulated by the dampers 45 and 46. This blast maintains the primary combustion of the coal which is coked. The steam in the blast prevents an 10 excessive temperature at this point on account of its endothermic reaction with the incandescent fuel. Further feeding of coal by the pusher 6 causes the partially consumed coked fuel to overflow from the retort on to the side grates. After the coal has passed out upon the side grates 41 the secondary blast is admitted to the ash pit 49 through the conduit 48 and the combustion regulated as conditions may require. It is understood that 15 20 25 the piston 7 is automatically reciprocated by steam which is controlled by a valve mechanism not shown.

The air which is supplied to the ash pit may be preheated to any desired degree and by 30 any suitable means. Water is circulated through the chamber 16 in the retort for the purpose of keeping the retort cool so that it will not be injured by the high temperatures produced, especially when preheated air is used. The cooling of the retort prevents 35 overheating of the same which overheating would cause the coal to coke and jam in the retort, especially if the motion of the pusher 6 should be stopped for any reason. In my 40 stoker the retort is provided with gently sloping slides and is therefore relatively flat. This together with the water cooling makes it possible to start the stoker without cleaning after a temporary shut down.

45 If one of the tuyère blocks 30 should become broken or other kind of repair to the tuyère should be necessary the tuyères may be removed from the furnace by disconnecting the upper portions of the pipes 42 and 43 and removing the tuyères as units. The repair having been made the tuyère is again placed in the stoker or a new tuyère may be substituted for the old.

If it is desirable to remove the stoker as a 50 unit for repairs or otherwise, this may be easily done by removing the filler blocks 50 and 51, thus allowing a small clearance between the door frame and the frame 11 whereupon the stoker may be removed from the furnace as a unit without disturbing any of the permanent setting of the furnace.

If necessary or desirable, the entire feeding mechanism of the stoker may be removed without disturbing the tuyères, retort or furnace setting. This is accomplished by re-

moving a few bolts which hold the parts together.

In assembling the tuyères, the blocks 30 are placed in position by sliding the tongues 31 and 32 in the grooves 26 and 27, in the 70 holders 25. After all the blocks 30 are in position, blocks 36 are placed on the ends of the holders and fastened by bolts 40.

The operation of the modification shown in Figures 7 and 8 is identical with that above 75 described with the exception of the air blasts. In the modification the blast is introduced into the wind box and the secondary blast is controlled by the gate 65 by opening that gate the desired amount. The primary blast is 80 introduced into the tuyères through the pipes 42^a and 43^a and if the air is preheated it may be moistened by introducing the water spray through the nozzles 67. By this arrangement the temperature of the retort area may be accurately controlled. From the foregoing it will be apparent that the primary and secondary blasts may be controlled independently 85 of each other. The secondary blast is controlled by the gate 65 and the primary blast 90 by the dampers 45^a and 46^a.

My invention has many advantages, among which may be mentioned that the primary blast is independent of the secondary blast; the proportions of air and steam in the primary blast may be varied; the temperature in the region of the retort may be controlled by controlling the primary blast; the secondary blast may be controlled and the combustion on the side grates accordingly 95 controlled; by the above means the combustion chamber may be kept free from clinker; the stoker as a unit is readily removable from the furnace without disturbing the setting; the tuyères may be individually removed as units 100 without disturbing the setting or the stoker; the feeding mechanism may be readily removed from the stoker without disturbing the tuyères or retort; the retort is cooled, thus enabling preheated air to be used in the 105 secondary blast; the structure is simple and rigid and repairs may be easily made.

I claim:

1. In a furnace, a wall having an opening therethrough, a stoker extending through the 115 opening into the furnace, the stoker having a retort, and a tuyère along the edge of the retort, the stoker having an opening from the interior to the exterior of the furnace through which the tuyère may be introduced 120 to or withdrawn from the furnace as a unit and without the removal of the stoker.

2. In combination with a furnace having an opening through a wall thereof, an under-feed stoker having a retort projecting into the furnace, tuyères supported by the retort, and a wall portion for the stoker substantially filling said opening, the cross-sectional dimensions of the retort and tuyères being smaller 125 than the opening whereby they may be re- 130

moved bodily from the furnace, the tuyères being separately removable through the wall portion of the stoker.

3. In combination with a furnace having an opening in a wall thereof, a tuyère comprising an open-sided body adapted to be passed through the opening into the interior of the furnace, an air connection for the tuyère body at the end of the body adjacent

said opening, and tuyère blocks fitting over the open side of the trough-like body to form a substantially enclosed air passage, the tuyère body with the blocks thereon being removable through said opening.

In testimony whereof I have hereunto set my hand.

OLIVER P. LUETSCHER.
